CLAIM

The ornamental design for a serving dish, as shown and described.

DESCRIPTION

FIG. 1 is a top perspective view of a serving dish;

FIG. 2 is a top plan view thereof;

FIG. 3 is a front elevational view thereof; the back elevational view being a mirror image thereof;

FIG. 4 is a bottom plan view thereof; and,

FIG. 5 is a left side elevational view thereof; the right elevational view thereof being a mirror image thereof.

1 Claim, 2 Drawing Sheets

FIG. 1

FIG. 2

FIG. 3

FIG. 4

FIG. 5
